UNITED STATES PATENT OFFICE.

WILLIAM R. MACINTOSH, OF BUFFALO, NEW YORK.

TAG-FASTENER.

1,156,489.

Specification of Letters Patent.

Patented Oct. 12, 1915.

Application filed September 22, 1914. Serial No. 862,953.

To all whom it may concern:

Be it known that I, WILLIAM R. MACINTOSH, a citizen of the United States, residing at Buffalo, in the county of Erie and 5 State of New York, have invented new and useful Improvements in Tag-Fasteners, of which the following is a specification.

This invention relates to wire fasteners for attaching tags or the like to articles for 10 identification or transportation.

It is the object of this invention to provide a fastener of this character which can be made at low cost, which can be put up in lots without liability of becoming tangled, 15 which permit of attaching tags to articles quickly and easily, and which hold the tags securely and reliably on the articles.

In the accompanying drawings: Figure 1 is a side elevation of a wire tag fastener constructed in accordance with my invention. Fig. 2 is a fragmentary longitudinal section of the same on an enlarged scale. Fig. 3 is a cross section in line 3—3, Fig. 2. Fig. 4 is a perspective view showing a tag attached 25 to an article by my improved fastener. Fig. 5 is a fragmentary longitudinal section showing the manner in which the ends of the fastener are connected when in use for attaching a tag to an article.

30 Similar characters of reference indicate corresponding parts throughout the several views.

My improved tag fastener is constructed from a single piece of wire which is so prepared that the same may be used for attaching a tag to an article by the use of the hands only instead of employing tools for this purpose.

In its general organization my improved 40 tag fastener comprises a longitudinal body 1, an enlarged loop or reversely bent part 2 connected at one end with one end of the body, and a coil 3 connected at one end with the other end of the loop and wound loosely 45 around that part of said body adjacent to the loop thereof, so that the convolutions of this coil are separated from each other, as shown in Figs. 1, 2 and 3. When using this fastener for attaching a tag to an article 50 the body of the fastener is passed through

the eye 4 of the tag 5 and a suitable part of the article, as for instance the handle 6 of a jug 7, and then the plain end 8 of the body is wrapped or wound preferably, closely and tightly upon the body so that the convolutions of the plain end of the body are arranged between the convolutions of the coil, as shown in Figs. 4 and 5.

The attachment of the tag to the article to be identified or transported is now complete and has been effected solely by hand. If any strains are applied to the fastener while thus secured to the tag and article tending to pull apart the connected ends of the fastener such strains would cause the 65 convolutions formed by winding the plain end of the wire to slip on the body toward the loop, thereby crowding together the convolutions of the coil toward the loop and causing the latter to form an 70 enlargement or head which frequently assumes the shape of a hook, whereby the two ends of the wire become firmly interlocked and are held against separation. The tag is thus securely attached to the article and 75 therefore not liable to become separated therefrom during shipment or other conditions. These fasteners can be bundled or packed in a condition in which the several 80 fasteners lie closely together without liability of the fasteners becoming interlocked or snarled which would make their separation preparatory to using them not only difficult but also annoying and involve loss of 85 time in tagging articles.

I claim as my invention:

A tag fastener comprising a wire having a body, and a coil forming a continuation of one end of the body and wound loosely around the adjacent part of the same and 90 having its convolutions separated from each other to permit the opposite end of said body to be wound upon the same between the convolutions of said coil.

Witness my hand this 21st day of September, 1914.

WILLIAM R. MACINTOSH.
